CLAIM

The ornamental design for a two-handled exercise device, as shown and described.

DESCRIPTION

FIG. 1 provides a top plan view of a two-handled exercise device.

FIG. 2 provides a front view of the two-handled exercise device of FIG. 1.

FIG. 3 provides a left view of the two-handled exercise device of FIG. 1.

FIG. 4 provides a bottom plan view of the two-handled exercise device of FIG. 1.

FIG. 5 provides a right view of the two-handled exercise device of FIG. 1.

FIG. 6 provides back view of the two-handled exercise device of FIG. 1.

FIG. 7 provides a first perspective view of the two-handled exercise device of FIG. 1.

FIG. 8 provides a second perspective view of the two-handled exercise device of FIG. 1.

FIG. 9 provides a third perspective view of the two-handled exercise device of FIG. 1; and,

FIG. 10 provides fourth perspective view of the two-handled exercise device of FIG. 1.

The broken line showing of parts of the drawings is included for the purpose of illustrating use and environment and forms no part of the claimed design.

1 Claim, 10 Drawing Sheets
